[57] CLAIM

The ornamental design for a mirror with hooks, as shown and described.

DESCRIPTION

FIG. 1 is a perspective view of a mirror with hooks showing our new design, the broken-line disclosure of a razor being for illustrative purposes only and forms no part of the claimed design;

FIG. 2 is a front elevational view of the mirror with hooks shown in FIG. 1;

FIG. 3 is a right side elevational view of the mirror with hooks shown in FIG. 1, the left side elevational view being the mirror image thereof;

FIG. 4 is a top plan view of the mirror with hooks shown in FIG. 1;

FIG. 5 is a rear elevational view of the mirror with hooks shown in FIG. 1; and,

FIG. 6 is a bottom plan view of the mirror with hooks shown in FIG. 1.
